CLAIM

The ornamental design for a foldable light emitting mat, as shown and described.

DESCRIPTION

FIG. 1 is a perspective view of the foldable light emitting mat showing the new design;

FIG. 2 is a top plan view thereof, the bottom plan view being a mirror image of the top plan view;

FIG. 3 is a front elevation view thereof;

FIG. 4 is a right elevation view thereof, the left elevation view being a mirror image of the right elevation view;

FIG. 5 is a rear elevation view thereof;

FIG. 6 is a front perspective view of the foldable light emitting mat shown in a second, folded configuration;

FIG. 7 is a rear perspective view thereof;

FIG. 8 is a right elevation view of thereof;

FIG. 9 is a left elevation view of thereof; and,

FIG. 10 is a perspective view of the foldable light emitting mat shown in a third, folded configuration.

The broken line showing in the drawings is included for the purpose of illustrating unclaimed portions of the foldable light emitting mat and forms no part of the claimed design.

1 Claim, 8 Drawing Sheets
